[57] CLAIM

The ornamental design for a golf greens repair tool, as shown and described.

DESCRIPTION

FIG. 1 is a front view of a golf greens repair tool showing my new design, the rear, except for the slant of the head, being a mirror image;

FIG. 2 is a side view thereof;

FIG. 3 is a reduced view of the opposite side thereof, the broken lines being for illustrative purposes only and forming no part of the claimed design;

FIG. 4 is an enlarged top view thereof; and,

FIG. 5 is a bottom view of FIG. 4.
